PROGRESSIVE ILLUMINATING MEANS

Leonard E. Ludvigsen, Los Angeles, Calif., assignor to Mega Corporation, Los Angeles, Calif., a corporation of California

Application June 23, 1947, Serial No. 756,439

10 Claims. (Cl. 315—320)

1

The present invention relates to improvements in progressive illuminating means.

More particularly the present invention relates to installations employing gaseous tubes which may be illuminated when supplied with electric current. One or more of such tubes may be employed in the practice of the present invention for illumination progressing from point to point and repeating itself cyclically.

An object of the present invention is to provide improved progressive illuminating means embodying mechanism which is sturdy and not likely to get out of order.

A further object is to provide progressive illuminating means employing hot cathode tubes which illuminating means are certain in operation and avoid the necessity for excessively high voltages.

A further object is to provide progressive illuminating means well adapted to meet the needs of commercial service.

Further objects will appear as the description proceeds:

Referring to the drawings:

Figure 1 is a diagrammatic view illustrating a system embodying the principles of the present invention;

Figure 2 is a diagrammatic view illustrating a detail of construction;

Figure 3 illustrates diagrammatically a resonant and holding relay employed in the system illustrated in Figure 1; and

Figure 4 illustrates diagrammatically another type of resonant and holding relay employed in the system illustrated in Figure 1.

According to the present invention, a plurality of gaseous tubes may be employed such, for example, as those indicated by the numerals 11, 12 and 13. Each of said tubes is provided with a cathode 14 which may be heated from a source of electric current. Within each of said tubes 11, 12 and 13 is a contact assembly indicated generally by the numeral 15. Each of the contact assemblies 15—15 includes a group of anodes indicated by the numerals 16, 17, 18 and 19 spaced along the length of the corresponding tube. Also included in each tube is an end anode 20. Each contact assembly 15 and the end anode 20 may be supported interiorly of the corresponding tube by any preferred means. Each of the anodes 16, 17, 18 and 19 is carried by a support 21 (Figure 2) and is provided with the movable electric contact 22. The anodes 16, 17 and 18 are each adapted to have electrical connection with the next succeeding anode through the contact 22, which is

biased into engagement with the relatively fixed contact 23, electrically connected to the next succeeding anode. Each anode is connected to its corresponding electrical contact 22 through a swinging arm 24 which carries a small mass of magnetic material indicated by the numeral 25.

Disposed in proximity to each of the masses of magnetic material 25 is a resonant coil 26 carried by a support 27. Each of the resonant coils 26 is adjustable whereby to respond selectively to a predetermined frequency, and for providing such adjustability each coil 26 is provided with a movable core 28, the amount of insertion of the core 28 into the coil 27 being selectable by means of the finger grip 29. To facilitate adjustment, the shank of the core 28 may have threaded engagement with the support 27. It will be understood that the frequency at which each particular coil 26 will respond may be chosen within relatively wide limits by the operator by adjustment of the core 28 within the coil 26.

The system disclosed in Figure 1 employs a plurality of relays 29, 30 and 31, which for convenience of description, may be referred to as "resonant and holding" relays. Each of said relays 29, 30 and 31 may be set at the will of the operator to respond to a predetermined frequency and to remain in operated condition as long as current is passing through the particular tube controlled by that particular "resonant and holding" relay.

Figure 3 illustrates one of the "resonant and holding" relays 29, 30 or 31. This relay is illustrated as having an approximately U-shaped field structure indicated by the numeral 32 and with the pivoted armature 32'. Said armature 32' carries a contact member 33 adapted to engage the stationary contact member 34. Said armature 32' is biased as, for example, by the spring 35 to a position wherein the contact 33 engages the contact 34. Each of the relays 29, 30 and 31 is provided with a pair of coils, one indicated by the numeral 36, being a resonant coil responsive to a predetermined frequency. The other coil, indicated by the numeral 37, is a holding coil for maintaining the relay in operated position whereby to hold the contact 33 out of engagement with the contact 34. The adjustment of the resonant coil 36 may be accomplished by adjusting the core 38 within said coil 36, this adjustment being facilitated by a screw driver slot 38' in one end of the core 38.

Co-operating with the resonant and holding relays 29, 30 and 31 are other resonant and hold-

ing relays 39, 40 and 41, the salient features of which are illustrated diagrammatically in Figure 4. Each of the resonant and holding relays 39, 40 and 41 is provided with an approximately U-shaped field structure indicated by the numeral 42 and with the swinging armature 43. Said armature 43 carries a pair of electrical contacts 44 and 45. Said armature 43 is biased as, for example, by a spring 46 into a position wherein the contact member 44 engages a relatively fixed contact 47 and wherein the contact 45 engages a relatively fixed contact 48. When said armature is in magnetized condition, said contact member 44 is moved into engagement with the relatively fixed contact 49 and the contact member 45 is moved into engagement with the relatively fixed contact 50, which contact 50 is a dead contact. A resonant coil 51 is provided, the functions of which may be varied by adjustment of the movable core 52, and the frequency at which the resonant coil 51 will respond may be chosen by varying the position of said core 52. The numeral 53 indicates a holding coil for holding the armature 43 in its attracted position so long as current is passing through said holding coil.

Proceeding now with a description of the system illustrated in Figure 1, the numerals 51-51 indicate the two sides of a source of alternating current electrical supply controlled by means of the switch 52. Said supply lines 51-51 are connected to the conductors 53-53 across which are connected the terminals of a self-starting alternating current motor 54 which motor 54 is adapted to swing a contact arm 55 along a segment 56 which may extend throughout part of the circumference of a circle. Said motor 54 is also adapted to move the core 57 relative to a frequency changer 58.

Also connected across the conductors 53-53 is the primary 59 of a transformer 60. Said transformer 60 is provided with the secondary 61 adapted to supply the full wave rectifying tube 62. Said transformer 60 is also provided with the secondary 63 for providing heating current for the tube 62. Said transformer 60 may be provided with other secondaries for heating other tubes in the system.

The frequency changer 58 is connected across the oscillator tube 64 which through the transformer 65 supplies oscillations to the push-pull amplifier 66. Said push-pull amplifier 66 through the transformer 67 delivers alternating impulses to the conductors 68-68 across which are connected the resonant relays 26-26 which, as stated above, are adjustable to respond to predetermined frequencies. Inasmuch as the frequency in the alternations in the conductors 68-68 varies with the position of the core 57 in the frequency changer 58, the resonant relays 26-26 may be adjusted to respond cyclically in response to variations in the position of the core 57 relative to the frequency changer 58.

Also connected across the conductors 53-53 is the primary 69 of a transformer 70 having a plurality of secondaries 71, 72 and 73 connected respectively to supply heating current to the cathodes 14 of the tubes 11, 12 and 13.

According to the disclosure chosen for illustration one uni-directional power source, indicated by the numeral 74, is provided for supplying current to tubes 11 and 12 and a separate uni-directional power source, indicated by the numeral 75, is provided for supplying current to the tube 13. The power source 74 is provided with a transformer 76, the primary of which is

adapted to be connected through the switch arm 55 and the segment 56 across the conductors 53-53. Uni-directional power source 75 is provided with a transformer 77, the primary of which is also adapted to be connected through the switch arm 55 and the segment 56 across the conductors 53-53. Each of said uni-directional power sources 74 and 75 is provided with a full wave rectifying assembly, indicated by the numerals 78 and 79, respectively, and each provides pulsating uni-directional current as indicated by the plus (+) and minus (-) signs adjacent thereto.

When the resonant and holding relays 29, 30, 31, 39, 40 and 41 are in their biased positions, that is, with the armatures thereof spaced from the field structures thereof, each of the uni-directional power sources 74 and 75 will be short-circuited. In other words, a by-pass circuit is provided for each of the tubes, said by-pass circuit having contact members adapted selectively to control the passage of current past or to the tubes. For example, the uni-directional power source 74 is connected through the positive lead thereof to the fixed contact 34 of the relay 38, through the armature 32' thereof to the movable contact 45 of relay 40 to the contact 48 thereof (electrically connected to the cathode 16 of tube 12) to the relatively fixed contact 34 of the relay 29, thence through the armature 32' thereof to the movable contact 45 of the relay 39 to the contact 48 thereof (electrically connected to the cathode 16 of tube 11), thence to the negative side of the uni-directional power source 74. The uni-directional power source 75 is short-circuited through the following circuit: from the positive lead thereof to the fixed contact 34 of the relay 31 through the armature 32' thereof to the movable contact 45 of the relay 41 through the contact 48 thereof (electrically connected to the cathode 16 of tube 13) back to the negative side of the uni-directional power source 75.

When the operator desires to set the system into operation, he will close the switch 52, energizing the conductors 53-53 and the self-starting motor 54. The arm 55 may be in any position throughout its circumferential range of movement and the core 57 will be in a corresponding position, depending upon the position of these instrumentalities when the system had previously been shut down.

For simplicity of explanation, the cyclic operation of the system may be assumed to start at a moment when the arm 55 is out of contact with the segment 56 and the core 57 is in a position to cause the frequency changer 58 to develop a relatively low frequency at which none of the resonant coils will respond. Operation of the motor 54 will bring the arm 55 into electrical contact with the segment 56 and will cause the frequency changer 58 to develop a frequency at which the relay 29 will respond, causing the resonant coil thereof to attract the armature 32', breaking engagement between the contacts 33 and 34 of said relay 29. This action will interrupt the short-circuit across the uni-directional power source 74 and current will now pass from the positive side of the uni-directional power source 74 through contact 34 of relay 38 through armature 32' thereof through the contacts 45 and 48 of relay 40 through contacts 44 and 47 of relay 39 through the holding coil 37 of the relay 29 through the contact assembly 15 of tube 11 to the anode 16 thereof adjacent to the cath-

ode 14 of said tube. Inasmuch as the cathodes 14-14 in each of the tubes will be heated by current from the transformer 69, current will flow between said anode 16 and the cathode 14 in tube 11 producing a glow in this part of tube 11, which glow will be maintained by reason of the fact that the holding coil 37 of the relay 29 maintains said relay in its attracted position, thereby maintaining the circuit just traced.

As the frequency changer 58 is operated further by the motor 54, the frequency impressed across the conductors 68-68 will be changed and the relay 29 will no longer be responsive to the frequency being developed but the holding coil thereof, being energized, will hold said relay in its unbiased or attracted position. It may be assumed that the next relay to respond is that relay 26 which controls the connection of anode 16 of the tube 11. When a frequency is developed across the conductors 68-68 at which the last mentioned relay will respond, the mass of metal 25 connected to the arm 24 associated with said anode 16 will be attracted, breaking circuit between the corresponding contacts 22 and 23 (Figure 2) whereby current in the contact assembly 15 in passing to the cathode 14 in tube 11 must pass from the anode 17 in said tube, resulting in a glow in said tube between anode 17 and cathode 14. As the relays 26-26 associated with the anodes 17 and 18 respond to the frequencies developed across the conductors 68-68, the glow will progress until it resides between the anode 19 and the cathode 14 in the tube 11.

The next relay to respond to frequency changes is the relay 39 which will move its contacts 44 and 45 out of engagement with the contacts 47 and 48 and into engagement with the contact 49 and the dead contact 50, respectively. This action disconnects electrode assembly 15 of the tube 11 and at the same time passes current from the uni-directional source 74 through the contacts 34 and 33 of relay 30 to the movable contact 45 of relay 40 through the contact 48 to the contact 44 of relay 39 through the contact 49 and holding coil 53 of relay 39 to the anode 20 in tube 11. The tube 11 will now glow throughout its length.

As the frequency changer proceeds in its action, the next relay to respond is the resonant and holding relay 30. The progression of illumination along the tube 12 will occur as the frequency developed by the frequency changer 58 varies in the same manner as described in connection with tube 11 until tubes 11 and 12 will be illuminated throughout their lengths.

The next relay to respond to changes in frequency is the relay 31 which will be operative, when energized, to start the progression of illumination of the tube 13 from the uni-directional power source 75 in like manner to that described in connection with tube 11.

After all of the relays have been operated to accomplish the complete illumination of all of the tubes in the system, the arm 55 will pass out of electric engagement with the segment 56 and the core 57 will be withdrawn from operative position in the frequency changer 58 and the parts will be restored to their positions for re-starting the cycle.

This cyclic operation will continue as long as the switch 52 is maintained in closed position.

When it is desired to discontinue operation of the system, it is necessary only to open the switch 52 at which time the entire system will

be de-energized. Upon closure of the switch 52 the progression of illumination will start from the point at which the switch 52 has been opened.

Though a preferred embodiment of the present invention has been described in detail, many modifications will occur to those skilled in the art. It is intended to cover all such modifications that fall within the scope of the appended claims.

What is claimed is:

1. In a progressive illuminating system, in combination, a tube provided with a cathode and a plurality of anodes spaced along said tube, switch means connecting said anodes together and means responsive to changes in electrical frequency for controlling said switch means for selectively charging said anodes.
2. In a progressive illuminating system, in combination, a tube having a cathode and a plurality of anodes spaced therealong, a contact assembly in said tube, switch means adapted to control the connections between said anodes, conducting means for delivering current to said contact assembly and electrical frequency responsive means for controlling said switch means.
3. In a progressive illuminating system, in combination, a tube provided with a cathode and a plurality of anodes spaced along said tube, means including switch means separably connecting said anodes to one another, electrical frequency responsive means for controlling said switch means and conducting means for delivering current to said anodes and switch means.
4. In a progressive illuminating system, in combination, a tube provided with a cathode and a plurality of anodes spaced along said tube, electrical conducting means connecting said anodes to one another, means for delivering current to said anodes and connecting means, electromagnetic means for controlling said connecting means, by-pass means adapted selectively to bypass said tube or to deliver current to said tube, and means responsive to predetermined frequencies for controlling said by-pass means and for controlling said electromagnetic means for progressively opening said connecting means for controlling discharge from said anodes in progression.
5. In combination, a tube having a cathode and anodes spaced along said tube, electrical conducting means connecting said anodes to one another, means for delivering current to said anodes and connecting means, by-pass means adapted selectively to bypass said tube or to deliver current to said tube and relay means selectively responsive to different electrical frequencies for controlling said by-pass means and said connecting means to cause discharge from said anodes in progression.
6. In combination, a tube having a cathode and a plurality of anodes spaced along said tube, separable contacts connecting said anodes, means for delivering current to said anodes and said contacts, magnetic means for controlling said contacts, said magnetic means being selectively responsive to different electrical frequencies.
7. In combination, a tube having a cathode and a plurality of anodes spaced along said tube, separable contacts connecting said anodes, means for delivering current to said anodes and said contacts, magnetic means for controlling said contacts, said magnetic means being selectively responsive to different electrical frequencies, by-pass means adapted selectively to bypass said tube or to deliver current to said tube and relay means responsive to predetermined electrical frequencies.

quencies for controlling said by-pass means and for maintaining said by-pass means in controlled condition while current is flowing in said tube.

8. In combination, a tube having a cathode and a plurality of anodes spaced along said tube, contact means connecting said anodes, conducting means for delivering current to said anodes and said contact means, magnetic means disposed exteriorly of said tube for controlling said contact means, a by-pass circuit disposed exteriorly of said tube and containing contacts controlling the passage of current selectively to or in by-passing relationship with said tube, said magnetic means being selectively responsive to predetermined electrical frequencies, said magnetic means being adapted selectively to open said by-pass circuit and said contact means.

9. In combination, a tube having a cathode and a plurality of anodes spaced along said tube, contact means connecting said anodes, magnetic means disposed exteriorly of said tube for controlling said contact means, a by-pass circuit disposed exteriorly of said tube and containing contacts controlling passage of current selectively to or in by-passing relationship with said tube, said magnetic means being selectively responsive to predetermined electrical frequencies and relay means responsive to predetermined electrical frequencies for breaking circuit through said by-

pass circuit and for maintaining said short-circuiting means in broken circuit condition as long as current is passing from one of said anodes to said cathode.

5 10. In a progressive illuminating system, in combination, a plurality of tubes each having a cathode and a plurality of anodes spaced therealong, a by-pass circuit for each of said tubes, said anodes in each of said tubes being connected together by contact means, magnetic means selectively responsive to predetermined frequencies for controlling said contact means and relay means selectively responsive to predetermined electrical frequencies for open-circuiting each of 15 said by-pass circuits and for maintaining said by-pass circuit in open-circuit condition while current is flowing in its corresponding tube and for connecting the end anode in one tube to the cathode in the next succeeding tube.
